[57] CLAIM

The ornamental design for a cosmetic marker, as shown and described.

DESCRIPTION

FIG. 1 is a right front perspective view of a cosmetic marker showing a first embodiment of our design;

FIG. 2 is a right front perspective view, with the cap removed to expose the rectangular extrusion stylus;

FIG. 3 is a top plan view shown without the cap for completeness of disclosure;

FIG. 4 is a right side elevation view thereof, the left side being a mirror image thereof;

FIG. 5 is a bottom plan view thereof;

FIG. 6 is a front end elevational view thereof;

FIG. 7 is a rear end elevational view thereof;

FIG. 8 is a front end elevational view of FIG. 1;

FIG. 9 is a right side elevational view of a second embodiment, wherein the modification resides in the appearance of the barrel; the left side being a mirror image of the side shown;

FIG. 10 is a front end elevational view of the second embodiment, shown with the cap in place;

FIG. 11 is a right side elevational view of a third embodiment, which is identical to the second embodiment except for the appearance of the rear end;

FIG. 12 is a rear end elevational view of the second and third embodiments; and,

FIG. 13 is a perspective view of the second and third embodiments.
